UNITED STATES PATENT OFFICE.

JOHN J. PENHALLEGON, OF MINERAL POINT, WISCONSIN, ASSIGNOR TO THE PEN-HALLEGON COMPANY, OF ST. PAUL, MINNESOTA, A CORPORATION OF SOUTH DAKOTA.

AUTOMOBILE-RADIATOR.

1,334,315.

Specification of Letters Patent.

Patented Mar. 23, 1920.

Application filed March 15, 1917, Serial No. 155,015. Renewed January 17, 1920. Serial No. 352,235.

To all whom it may concern:

Be it known that I, JOHN J. PENHALLEGON, a citizen of the United States, residing at Mineral Point, in the county of Iowa and State of Wisconsin, have invented certain new and useful Improvements in Automobile-Radiators, of which the following is a specification, reference being had therein to the accompanying drawing.

10 This invention relates to improvements in radiators, and has for its object the furnishing of a simple and efficient means for fastening the radiator, together with a separate inclosing shell or casing, with the upper member or frame of a motor vehicle.

As will be recalled by workers in the art to which the invention relates, it is fast becoming the practice to employ in connection with the radiator proper or core, a separate 20 outside casing that may be properly painted and finished, to the end that, as compared to directly painting the core, the painted or finished surface may be removed from the intimate influence of the heat created by the 25 radiator in action, and thereby preserved.

With this in mind, it is my present aim to provide an improved single fastening device, adapted, as stated, not only to secure the core in proper position upon the supporting 30 member provided therefor, but also to secure at the same point the base of the separate casing or shell.

The preferred embodiment of the invention presents what may be styled a double- 35 stem bolt of different diameters threaded on both portions thereof, to accommodate suitable binding nuts, and the end of the stem of greater diameter serving as a head for the smaller stem. When employed in keeping 40 with my present purposes, the smaller stem may be passed through a suitable opening provided therefor in the supporting frame, and a nut applied to the lower end of the stem to bind the device on the frame. An 45 apertured flange on the radiator core may then be slipped over the enlarged stem portion, as may also be the case with the casing or shell, and finally another nut may be engaged with the upwardly protruding end of 50 said larger stem to bind the superposed flanges of the radiator core and casing upon the supporting frame member.

For the purposes of rendering a better understanding of the invention, the preferred 55 embodiment thereof, to which I have allud-

ed, is illustrated in the accompanying drawings forming part hereof, and from which the details of construction and arrangement of parts will be clear when considered in the light of the following more specific description.

In the drawings:

Figure 1 is a fragmentary face view of a radiator provided with the present improvements;

Fig. 2 is a rear view of the same;

Fig. 3 is an edge view, and,

Fig. 4 is a vertical sectional view.

Referring more specifically to the drawings wherein like reference letters designate the same parts in the several views, A indicates the core or body of the radiator, the same being provided with outwardly extending supporting and securing flanges or lugs B, at opposite edges thereof, and C represents the separate outside shell or casing provided with similarly outwardly projecting supporting and securing flanges D, adapted to be superimposed upon the flanges or lugs B, all of the lugs and flanges B, D, being provided with smooth open portions E, adapted to aline in the respective opposite pairs, as shown. F is a transverse supporting frame member of the vehicle, having the depressed central portion to receive the base 70 a of the radiator proper or core, the frame member being turned upwardly, as at f, to engage the edges of said base a, and then turned outwardly, as at f' to afford the horizontal supporting ends f'' adapted to lie parallel with the lugs B and flanges D to support said lugs and flanges thereabove and thereon.

The end portions f' of the supporting frame member are provided with smooth 95 openings G, of a diameter considerably less than the diameter of the openings E in the lugs and flanges previously discussed.

Inasmuch as the fastening means at the opposite sides of the radiator are identical in both instances, a description of one will suffice for both. H is the smaller end of what I have termed a double-stem securing bolt, this end being threaded, as at h, so that a nut J may be threaded upwardly thereon in a rotary movement to the right, as shown. This reduced stem portion H is adapted to pass through the openings G in the end of the supporting frame member and the bolt is supported from passing 100 105 110

through said frame member, by a shoulder or head K, to abutting the upper face of the frame member in opposition to the clamping nut J, by increasing the diameter of the device to provide the larger stem portion L, the same being threaded as at l, in a direction opposite to the threading of the reduced stem portion H, so that in this instance also a binding nut M may be forced 10 home by a turning movement to the right, as usual in applying a nut to the ordinary bolt.

The larger stem portion L, when the device is initially clamped to the frame member, constitutes in a sense a permanent fit on the frame and serves as an upwardly projecting stud over which the flange B and flange D may be slipped, enabled by their aligned openings, and the radiator and casing 20 or shell may then be securely bound in place by the application of the nut M, as will be clear.

Any one experienced with the assembling of automobile parts knows that great 25 convenience is frequently encountered by the falling of the bolts or nuts into the drip pan or interior closely related parts of the mechanism, and it will be correspondingly appreciated that by the provision of my 30 present fastener it will practically never be necessary to release the fastener from the supporting frame member F, unless in rare instances, the studs should become broken or its thread l impaired.

35 To remove the casing C or the radiator A, it is simply necessary to remove the nuts M and lift the casing, or the casing and the radiator, as the case may be, off the studs the entire operation takes places from the exterior of the vehicle, where there is plenty 40 of room for the work.

While I have herein disclosed a specific embodiment of the invention, it will be clear that the same is capable of embodiment in 45 other forms and devices as may fall within the terms of the hereto appended claims.

Having thus described the invention, what is claimed is:

1. In a radiator, a supporting member 50 provided with a horizontally extending apertured flange, a radiator part to be supported thereby having an outstanding apertured flange fitting upon the flange of the supporting member, a vertically extending 55 double stem bolt having its reduced portion passed through the aperture in the flange of the supporting member and threaded for the accommodation of a nut, a nut engaging the stem to clamp the bolt to the 60 flange of the supporting member, the enlarged portion of the bolt passing through the apertured flange of the radiator part, and means engaging said enlarged portion

of the stem bolt to clamp the flange of the radiator part to the flange of the supporting member. 65

2. In a radiator, a supporting member provided with an outwardly extending apertured flange, a radiator part to be supported thereby and having an outstanding apertured flange fitting upon the flange of the supporting member, a double stem bolt having its reduced portion passed through the opening of the flange of the supporting member and threaded for the accommodation 70 of a nut, a nut engaging the same to clamp the bolt to the flange of the supporting member, the enlarged portion of the bolt passing through the apertured flange of the radiator part, and means engaging 75 said enlarged portion of the bolt to clamp the flange of the radiator part to the flange of the supporting member, said last mentioned means including an oppositely threaded surface on the enlarged portion of the bolt, and a nut engaging the same. 80

3. In a radiator, a supporting member provided with an outwardly extending apertured flange, a double stem bolt having its reduced end secured to the flange of the 90 supporting member with the under face of the enlarged portion engaging the upper face of the flange of the supporting member, a radiator core member having an outstanding apertured flange fitting over the enlarged end of the bolt and resting upon the flange of the supporting member, a casing part provided with an outstanding apertured flange fitting over the enlarged end of the bolt and resting upon the flange of the 95 radiator core member, and means engaging said enlarged portion of the bolt for clamping the flanges of the core member and the casing to the flange of the supporting member. 100

4. In a radiator, a supporting member provided with an outwardly extending apertured flange and having an upwardly projecting stud, a radiator part provided with an outstanding flange fitting over the stud 110 and resting against the flange of the supporting member, and means engaging the stud for clamping the flange of the radiator part to the flange of the supporting member, in combination with a radiator casing 115 member provided with an apertured outstanding flange secured by said clamping means between the same and the flange of the radiator core part. 120

In testimony whereof I hereunto affix my signature in the presence of two witnesses.

JOHN J. PENHALLEGON.
